FOREIGN PATENT DOCUMENTS

CN 309171752 * 3/2025

Primary Examiner — Paula Allen Greene*(74) Attorney, Agent, or Firm* — St. Onge Steward Johnston & Reens LLC; Stephen P. McNamara(57) **CLAIM**

The ornamental design for a sound attenuator as shown and described.

DESCRIPTION

FIG. 1 is a front, top and left side isometric view of a sound attenuator in accordance with the new design with its push button actuator in an open position;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a bottom plan view thereof;

FIG. 7 is a top plan view thereof;

FIG. 8 is a front elevation view thereof with its push button actuator in a closed position;

FIG. 9 is a left elevation view thereof; and,

FIG. 10 is a front, top and left side isometric thereof.

1 Claim, 10 Drawing Sheets(56)
